UNITED STATES PATENT OFFICE.

EUCLID P. WORDEN, OF GLEN RIDGE, NEW JERSEY, ASSIGNOR TO WORTHINGTON PUMP AND MACHINERY CORPORATION, OF NEW YORK, N. Y., A CORPORATION OF VIRGINIA.

SURFACE CONDENSER.

Application filed August 3, 1926. Serial No. 126,790.

This invention relates to steam condensers of the surface type, and the primary object of the invention is to provide a condenser in which leakage of cooling water, circulated 5 through the tubes of the condenser, into the steam chamber and its mixing with the condensate will be prevented.

In steam condensers the temperature of the tubes is constantly fluctuating and the difference between the temperature of the tubes adjacent to the steam inlet and those remote therefrom, of a condenser operating with the varying load is constantly fluctuating through a wide range. Because of this it has 15 heretofore been the practice to provide stuffing box connections for one or both ends of the tubes with the tube heads in order to accommodate the expansion and contraction of the tubes. Such stuffing box connections 20 are objectionable for various reasons, one of which is the difficulty in avoiding leakage, especially as the temperatures to which they are sometimes subjected are so high as to injuriously affect the packing in the stuffing 25 boxes so that leakage results. In the present pure water power plant systems, where boiler feed water is purified by degasification, etc., to eliminate to the greatest possible extent corrosion and other detrimental actions on 30 the boiler tubes, pumps, etc., employed in the power plant, it is highly desirable to prevent the circulating cooling water, which is not treated for purification, from leaking from the tubes and mixing with the condensate or boiler feed water as such mixing 35 counteracts to a certain extent the action of the purifying mechanism of the system.

To overcome such leakage it is necessary to provide fluid tight connections between the 40 tubes and tube heads of the condensers, and in so doing cognizance must be taken of and compensation made for variances in the temperatures in the condenser, variances in the expansion and contraction relation of the 45 tubes with the shell or casing of the condenser and also difference in temperatures locally within the condenser, whereby the tubes in one set or bank or in one location of the interior of the condenser will be subjected to greater or less temperatures and 50 temperature variances than tubes in another part of the condenser.

It is an object of the present invention to provide a condenser construction which will 55 permit a fluid tight connection between the

tubes and tube heads and will compensate for variances in temperatures and conditions as outlined above.

The present invention embodies essentially a condenser having a floating water box to 60 which one of the tube heads is attached, which is connected to the condenser shell or casing by a flexible or expansion joint to permit movement of the water box and tube head relative to the condenser shell upon expansion and contraction of the condenser tubes under heat variances, and also embodies means for supporting the movable water box and tube head in relation to the condenser shell in such manner as to permit 70 greater movement of one part of the water box than another to compensate for unequal expansion and contraction of the tubes due to different temperatures in different parts of the condenser. 75

With these objects in view, the invention consists in various features of construction and combination of parts, which will be first described in connection with the accompanying drawings, showing a surface condenser 80 of the preferred form embodying the invention, and the features forming the invention will be specifically pointed out in the claims.

In the drawings—

Figure 1 is a side elevation of a surface 85 condenser constructed in accordance with this invention.

Figure 2 is an enlarged fragmentary section through the condenser illustrating the expansion joint. 90

Figure 3 is an enlarged detail in side elevation of the supporting connection between the water box and condenser shell which permits compensating movement of the water box and. 95

Figure 4 is an end elevation of the compensating supporting connection.

Referring more particularly to the drawing, the steam condenser, which is of the surface type, embodies the shell 1 into which the steam passes through the exhaust inlet tube and in which it is condensed through the cooling action of cooling water circulating through the tubes 3 which extend from the water box 4 to the water box 5. The 100 condensate passes to the hotwell 6 from which it is taken in the approved manner. The tubes 3 through which the cooling water is circulated are carried by suitable tube heads within the condenser and in the pres- 105 110

ent invention they are expanded into the tube heads, welded to the tube heads, or otherwise attached so as to form a fluid tight joint to prevent leakage of the circulating cooling water into the condensing chamber. Owing to variances in temperatures in the condenser the tubes 3 will have fluctuating expansion and contraction and the force of such expansion and contraction is so great that if both of the tube heads were rigidly mounted, such expansion and contraction would break the connection of the tubes with the heads, break the heads or tubes and destroy the effectiveness of the condenser.

15 To compensate for the expansion and contraction of the tubes 3 and the tube head 7, which is attached to the water box 5 in any suitable manner, is connected to the shell 1 by an expansion joint 8. The expansion joint 8 is preferably formed of flexible material of a composition of rubber but any suitable material may be employed which will permit of movement of the tube head 7 and water box 5 relative to the casing 1.

20 The strip of material of which the expansion joint 8 is formed is attached to the tube head 7 and the casing 1, respectively, by binding rings 9 and nuts 10, as clearly shown in Figure 2 of the drawings.

25 Bolts 11 are threaded into the casing 1 and extend slidably through the flange 12 on the water box 5. Springs 13 are coiled about the bolts 11 and engage the casing 1 and the flange 12, the said springs being provided to

30 sustain pressure of the atmosphere and they are set to put the initial tension on the tubes 3 to facilitate the sensitiveness of the action of the expansion joint 8. Nuts 14 are threaded on the bolts 11 and by adjustment of these nuts the expansive action of the springs 13 and of the expansion joint 8 may be limited.

In surface condensers the tubes at the top of the condenser or adjacent to the inlet of the exhaust steam are subjected to higher temperatures and greater temperature fluctuations than the tubes at the bottom of the condenser, where the condenser operates under varying loads, and because of this condition the tubes in different parts of the condenser will have different degrees of expansion and contraction causing unequal movement of the tube head 7 and water box 5 at different parts of the tube head and water box, and owing to the relatively great weight of the water box and tube head, it is necessary to provide a supporting connection between the water box and the casing which will permit of supported unequal movement of the water box. One form of the supporting compensating structure, as shown in Figures 1, 3 and 4 of the drawings, wherein brackets 20 are attached by bolts, cap screws or the like 21 to lugs 22 formed

55 on the water box 5. The brackets 20 have

depending knife edge bearing members 23 on their lower ends which have knife edge engagement in hardened steel blocks 24 carried by the bearing members 25. The bearing members 25 rest upon rollers 26 which are supported upon the upper flat faces 27 of brackets 28. The supporting brackets 28 are attached to the condenser shell 1 in any suitable manner. The knife edge engagement between the knife edge bearings 23 and the supporting members 25 will permit pivotal movement of the water box 5 relative to the condenser shell or casing 1, while the rollers 26 will provide sliding supports which will permit the water box to move longitudinally relative to the casing 1 and thereby providing both pivotal and slideable supports for the water box 5 relative to the casing 1 for relieving the expansion joint 8 of the stress of the weight of the water box 5.

From the foregoing description taken in connection with the accompanying drawings, it will be apparent that a condenser structure has been provided which will permit the tubes 3 through which the cooling water is circulated to be attached to the tube heads with fluid tight joints such as expansion of the tubes into the heads, and all expansion and contraction of the tubes due to heat variances within the condenser will be compensated for in such manner as to eliminate liability of the breakage of the joints between the tubes and tube heads and that a condenser structure has been provided in which leakage of the cooling water into the condensing chamber will be eliminated.

It will be understood that the invention is not to be limited to the specific construction or arrangement of parts shown but that these may be modified widely within the invention defined by the claims.

What is claimed is:

1. In a surface condenser, a shell, a water box, a tube head carried thereby, a flexible connection between the water box and shell, and atmospheric pressure sustaining means between said water box and shell.

2. In a surface condenser, a shell, a water box, a tube head carried thereby, a flexible connection between the water box and shell, and atmospheric pressure sustaining means between said water box and shell, and rockable supporting connection between said water box and shell.

3. In a surface condenser, a shell, a water box, a tube head carried thereby, a flexible connection between the water box and shell, atmospheric pressure sustaining means between said water box and shell, and rockable and sliding supporting connection between said water box and shell.

4. In a surface condenser, a shell, a water box, a tube head carried thereby, a flexible connection between the water box and shell,

- and rockable and sliding supporting connection between said water box and shell. 65
5. In a surface condenser, a shell, a water box, a tube head carried thereby, an expansion joint between said tube head and shell, and atmospheric pressure sustaining means between said water box and shell. 70
6. In a surface condenser, a casing, a water box, a tube head carried thereby, tubes having their ends expanded in said tube head, and an expansion joint between said tube head and shell, and rockable supporting connection between said water box and shell. 75
- 10 7. In a surface condenser, a shell, a water box, a tube head carried thereby, tubes having fluid tight connection with said tube head, an expansion joint between said tube head and casing, means for limiting the 80 expanding movement of said expansion joint and means for movably supporting said water box independently of said tubes and flexible joint. 85
- 20 8. In a surface condenser, a shell, a water box, a tube head carried thereby, tubes having fluid tight connection with said tube head, an expansion joint between said tube head and casing, means for limiting the expanding movement of said expansion joint, 90 and a rockable and sliding supporting connection between said water box and shell. 95
- 25 9. In a surface condenser, a shell, a water box movable independently of the shell, and a rockable connection between the water box and shell. 100
- 30 35 10. In a surface condenser, a shell, a water box movable independently of the shell and a rockable and slideable connection between the water box and shell. 105
- 40 11. In a surface condenser, a shell, a water box movable independently of the shell, supports on said shell, rollers on said supports, support members resting on said rollers, and rockable connections between 110 said support members and water box. 115
- 45 12. In a surface condenser, a shell, a water box movable independently of the shell, supports on said shell, rollers on said supports, support members resting on said rollers, rockable connections between said support members and water box, and an expansion joint between said water box and shell. 120
- 50 13. In a surface condenser, a shell, a water box movable independently of the shell, supports on said shell, rollers on said supports, support members resting on said rollers, brackets carried by said water box and having knife edge engagement with said support members to provide rockable connection between the water box and support members. 125
- 55 14. In a surface condenser, a shell, a water box movable independently of the shell, supports on said shell, rollers on said supports, support members resting on said rollers,
- brackets carried by said water box and having knife edge engagement with said support members to provide rockable connection between the water box and support members, and an expansion joint between said water box and casing. 130
- 60 15. In a surface condenser, a shell, a water box movable independently of the shell, supports on said shell, rollers on said supports, support members resting on said rollers, brackets carried by said water box and having knife edge engagement with said support members to provide rockable connection between the water box and support members, an expansion joint between said water box and casing, and means for limiting expanding movement of said expansion joint. 135
- 65 16. In a surface condenser, a shell, a water box movable independently of the shell, supports on said shell, rollers on said supports, support members resting on said rollers, brackets carried by said water box and having knife edge engagement with said support members to provide rockable connection between the water box and support members, an expansion joint between said water box and casing, and atmospheric pressure sustaining means between said water box and casing. 140
- 70 17. In a surface condenser, a shell, a water box, a tube head carried thereby, an expansion joint between said tube head and casing, and atmospheric pressure sustaining springs between said casing and water box. 145
- 75 18. In a surface condenser, a shell, a water box, a tube head carried thereby, an expansion joint between the tube head and shell, atmospheric pressure sustaining springs between said shell and water box, and means for limiting the action of said springs and for limiting the expanding movement of 150 said expansion joint. 155
- 80 19. In a surface condenser, a shell, a tube head, an expansion joint between said tube head and shell, tubes rigidly connected to said tube head, and means for applying initial tension on said tubes. 160
- 85 20. In a surface condenser, a shell, a water box, a tube head carried thereby, tubes rigidly connected to said tube head, an expansion joint between said tube head and shell, and means, engaging the shell and water box for applying initial tension on said tubes. 165
- 90 21. In a surface condenser, a shell, a water box, a tube head carried thereby, tubes rigidly connected to said tube head, an expansion joint between said tube head and shell, means engaging the shell and water box for applying initial tension on said tubes, and means for limiting the movement of said initial tension applying means. 170

In testimony whereof I affix my signature.
